(57) CLAIM

The ornamental design for a front face of a floor mat, as shown and described.

DESCRIPTION

FIG. 1 is a front, top and left perspective view of the front face of a floor mat according to the present invention; and, FIG. 2 is a front view of front face of the floor mat of FIG. 1.

The broken line showing of environment is for illustrative purposes only and forms no part of the claimed design.
